United States Patent Office

Des. 189,213
Patented Nov. 8, 1960

189,213

COIN OPERATED NEWSPAPER VENDOR OR SIMILAR ARTICLE

Raymond M. Terry, 5560 Ascot Drive, Oakland, Calif.

Filed Oct. 20, 1959, Ser. No. 57,986

Term of patent 14 years

I claim:

The ornamental design for a coin operated newspaper vendor or similar article, as shown.
